CLAIM

The ornamental design for a dual bulbous seal, as shown and described.

DESCRIPTION

FIG. 1 is a perspective view of a dual bulbous seal, in accordance with the present invention;

FIG. 2 is a front elevation view of the dual bulbous seal of FIG. 1, in accordance with the present invention;

The rear elevation view of the dual bulbous seal is a mirror image of that shown in FIG. 2;

FIG. 3 is a top plan view of the dual bulbous seal of FIGS. 1-2, in accordance with the present invention;

FIG. 4 is a left side elevation view of the dual bulbous seal of FIGS. 1-3, in accordance with the present invention;

FIG. 5 is a right side elevation view of the dual bulbous seal of FIGS. 1-4, in accordance with the present invention; and,

FIG. 6 is a bottom plan view of the dual bulbous seal of FIGS. 1-5, in accordance with the present invention.

The symbolic break lines depict the boundaries of the claim. The area between the break lines forms no part of the claimed design.
